SPECTACLE FRAME

Andrew C. Lenard, New York, N. Y.

Application August 25, 1955, Serial No. 37,661

Term of patent 7 years

(Cl. D57—1)

FIG. 1.

FIG. 2.

FIG. 3.

Fig. 1 is a front elevational view of a spectacle frame showing my new design;

Fig. 2 is a side elevational view thereof; and

Fig. 3 is a top plan view thereof.

The temple is shown broken away in Fig. 3 for convenience of illustration.

The dominant feature of my design resides in the portions shown in full lines.

I claim:

The ornamental design for a spectacle frame, as shown and described.
